SHADE UMBRELLA

Carl R. Meyer, 2512 E. Vine St.,
West Covina, Calif. 91790

Filed Dec. 17, 1965, Ser. No. 226

Term of patent 14 years

(Cl. D88—3)

FIG. 1 is a top plan view of a shade umbrella showing my new design; and

FIG. 2 is a partial sectional and side elevational view taken along line 2—2 of FIG. 1.

I claim:

The ornamental design for a shade umbrella, as shown.
